UNITED STATES PATENT OFFICE.

HAROLD SERRELL, OF PLAINFIELD, NEW JERSEY, ASSIGNOR TO THE
OVERMAN WHEEL COMPANY, OF BOSTON, MASSACHUSETTS.

CYCLE-LAMP.

SPECIFICATION forming part of Letters Patent No. 373,911, dated November 29, 1887.

Application filed February 5, 1887. Serial No. 226,661. (No model.)

To all whom it may concern:

Be it known that I, HAROLD SERRELL, residing at Plainfield, in the county of Union and State of New Jersey, have invented certain new and useful Improvements in Cycle-Lamps; and I do declare the following to be a full, clear, and exact description of the same, reference being had to the accompanying drawings, which form a part of this specification.

10 My invention relates to an improvement in cycle-lamps, the object being to produce a lamp burning with a bright clear flame and protected against accidental extinguishment.

With these ends in view my invention consists in certain details of construction and combinations of parts, as will be hereinafter described, and pointed out in the claims.

In the accompanying drawings, Figure 1 is a view of the lamp in vertical section through the side lights. Fig. 2 is a similar view through the head-light and reflector, with the oil-fount removed. Fig. 3 is a view in transverse section on the line *x x* of Fig. 1, with the oil-fount removed. Fig. 4 is a similar view on the line *y y* of the same figure. Fig. 5 is a like view on the line *z z* of the same figure; and Fig. 6 is a broken view in perspective of the fount, showing its draft-guard.

As herein shown, the lamp-frame *A* is provided at its lower end with an inner shell open in front for the reception and removal of the fount *B*, and comprising the bottom plate, *C*, the side plates, *D* and *E*, and the rear plate, *J*. The said plate *C* is imperforate and supports the fount. It extends to the rear of the frame *A*; but between its side edges and the sides of the frame are spaces, as shown. The side plates, *D* and *E*, are provided at their forward edges with flanges *F F*, which are closed into the frame, and at their upper edges with perforated flanges *G G*, also closed into the frame, the plate *E* being cut away, as at *H*, to receive the wick-spindle *I* of the wick-raiser applied to the oil-fount. It will thus be seen that these side plates are imperforate, except at their upper ends. The rear plate, *J*, is perforated at *K*, and provided at its upper edge with a perforated flange, *L*, which is located in part under the reflector *N*. The lower edges of the side plates, *D* and *E*, respectively, join the opposite side edges of the

bottom plate, *C*, while their rear edges join the opposite edges of the rear plate, *J*, the lower edge of which rests upon the said plate *C* at a point forward of its rear edge, which, 55 as has been stated, extends to the rear of the frame *A*.

Under the construction described side flues, *O O*, and a rear flue, *P*, are formed between the side and rear plates and the said frame, 60 and deliver air into the flame-chamber *Q* through the described perforations of the plates and in part at the level of the flame. The said side flues, *O O*, take air directly from an air-chamber, *R*, between the side edges of the 65 plate *C* and the frame, while the rear flue, *P*, takes air from the side flues and only from them, being cut off from the air-chamber *R* by the rear end of the said plate *C*. The said air-chamber is located below the bottom plate, 70 *C*, and between the same and a horizontal parallel perforated plate, *S*, located at the lower end of the frame *A*. An imperforate plate, *T*, located below the plate *S* and forming a guard therefor, is also secured to the lower 75 end of the frame, with which it is connected at its rear and forward edges, its ends being open, as at *U U*, to admit air to the perforated plate *S*, as shown.

A draft-guard, *V*, consisting of an upright 80 flat plate, is mounted upon two bent arms, *W W*, secured to the top of the fount, in position to bring the guard in front of the opening *X*, made in the frame *A* to receive the wick-spindle, which occupies the rear end of the 85 slot, the draft-guard being in front of it.

Air enters the lamp at *U U*, and, passing through the perforations of the plate *S*, enters the air-chamber *R*, from which it flows between the sides of the frame *A* and the adjacent edges of the plate *C* into the flues *O O*, 90 where it is diffused, a part of it issuing into the flame-chamber at about the level of the flame through the perforations of the flanges *G G* of the plates *D* and *E*, and a part passing around the rear edges of such plates and into the flue *P*, whence it is delivered into the flame-chamber through the perforations in the body and flange of such plate.

The whole lower part of the lamp becomes 100 heated from the flame, and the air, passing through the flues, herein provided for, and

hence between heated metallic surfaces, becomes considerably raised in temperature before it reaches the flame-chamber.

By heating the air, as described, it is better prepared for combustion, the flame is not chilled, and a more brilliant light is obtained, with a more perfect combustion of the illuminant. The heated surfaces also produce a current, insuring a continuous supply of air to the flame, and thus making its free burning largely independent of outside atmospheric conditions. Finally, under the described construction the force of the air entering the lamp is so broken that the accidental dropping of it, and the rush of air caused by wind or fast riding, will not create a partial vacuum and put out the light.

The imperforate guard plate T may, if desired, be dispensed with, as it is not essential to the successful operation of the lamp; and I would have it understood that I do not limit myself to the exact construction and arrangement of parts herein shown and described, but hold myself at liberty to make such changes and alterations as fairly fall within the spirit and scope of my invention.

Having fully described my invention, what I claim as new, and desire to secure by Letters Patent, is—

30 1. In a cycle-lamp, the combination, with a lamp-frame, of a shell located in the lower part of such frame, made open in front and including side, rear, and bottom plates, the side plates being imperforate except at their upper ends, and the bottom plate being also imperforate, and flues communicating with the flame-chamber of the lamp, being formed between the lamp-frame and the said side and rear plates and taking air at the lower ends of the former, and a current-breaker located below such shell and breaking the air before it enters the said flues, substantially as set forth.

2. In a cycle-lamp, the combination, with the frame thereof, of a shell located in the lower part of such frame, adapted to receive the oil-fount, provided with openings at or near its upper end, and comprising side and rear plates and an imperforate bottom plate, side and rear flues being formed between the respective plates and the lamp-frame for the passage of air which enters the flame-chamber through the openings in the shell, the rear flue communicating with and taking air only from the side flues, substantially as set forth.

3. In a cycle-lamp, the combination, with 55 the frame thereof, of a shell located in the lower part of such frame, adapted to receive the fount and comprising an imperforate bottom plate and perforated side and rear plates, side and rear flues communicating with and discharging air into the flame-chamber, being formed between such plates and the lamp-frame, and an air-chamber located below the said bottom plate, the side flues communicating with and taking air from such chamber and the rear flue 60 communicating with and taking air from the side flues and being cut off from the said air-chamber, substantially as set forth.

4. In a cycle-lamp, the combination, with a lamp-frame having the lower ends of its side walls imperforate, of a shell located in the lower part of such frame and including an imperforate bottom plate and side and rear plates, and a perforated plate located below the imperforate bottom plate of the shell, with an air-chamber 75 between it and the same, flues communicating with the flame-chamber of the lamp, being formed between the side and rear plates of the shell and the lamp-frame and taking air from the said air-chamber, substantially as set forth.

5. In a cycle-lamp, the combination, with a lamp-frame, of a shell including an imperforate bottom plate extending to the rear wall of the lamp-frame, side plates joining the edges 85 of such bottom plate and connected with the frame at their upper ends, and a rear plate connected at its upper end with the rear wall of the lamp-frame, at its lower end with the bottom plate at a point forward of the rear 90 end thereof and at its sides with the rear ends of the side plates, flues communicating with the flame-chamber of the lamp, being formed between such shell and the lamp-frame and taking air at the lower end of the side plates 95 of the former, and a current-breaker located below the bottom plate of the shell for breaking the air before it enters such flues, substantially as set forth.

In testimony whereof I have signed this specification in the presence of two subscribing witnesses.

HAROLD SERRELL.
